REGISTERING DEVICE FOR GASOLINE
TANKS

Moritz Gaertner, New York, N. Y.

Application July 20, 1932, Serial No. 623,542

1 Claim. (Cl. 235—94)

The present invention relates to a detecting and registering device for containers and especially for inlets to tanks for gasoline and the like.

5 It is an object of the present invention to provide a device which is capable of detecting and registering an act of adulteration or substitution of gasoline and the like.

Heretofore, complicated valves and locks have 10 been installed to prevent adulteration or substitution of gasoline and the like. If these valves and locks have been tampered with and opened, no record of the unauthorized act is made. It is essential and highly desirable to have a record 15 made of the aforesaid acts. As far as I am aware, the art has not been provided with a wholly satisfactory register.

It is another object of the present invention to provide a registering device which will register 20 the opening of the closure to the gasoline or other tank which can be checked and controlled from a central office or authorized agent.

It is a further object of the invention to provide 25 a registering device of the character described which is difficult or impossible to tamper with and which will not interfere with the filling of the gasoline tank or the like.

It is particularly within the contemplation of 30 the invention to provide a registering device for registering adulteration or substitution which is especially adapted to gasoline or oil tanks as well as other liquid containers which are liable to be subjected to adulteration or substitution.

Other objects and advantages of the invention 35 will become apparent from the following description taken in conjunction with the drawing, in which

Fig. 1 illustrates a top plan view of my registering device;

40 Fig. 2 is a sectional view of the improved device taken on the line 2—2 of Fig. 1;

Fig. 3 depicts a sectional view taken on the line 3—3 of Fig. 2;

45 Fig. 4 is a fragmentary elevational view of an upper part of my device showing certain detailed construction;

Fig. 5 is a sectional view of an upper portion of a modified embodiment of the present invention; and

50 Fig. 6 is a top plan view of a corrugated measuring stick which is capable of being used in connection with my device.

Generally speaking, the invention contemplates the provision of a registering device capable of 55 providing a registering indication by incorporat-

ing an indicator in the detecting apparatus at certain intervals. The indicator is dated and marked and replaced by a new one. The old indicator is taken to the central office of distributing agency for inspection and for filing. By treating the indicator with a suitable solution, its color or composition will be changed when gasoline or other liquid used in the tank comes in contact therewith. Substances for the aforesaid solution are well known to those skilled in the art. Thus, for instance, the indicator may be treated with an aniline dye such as chrysoidine having a formula of $C_{12}H_{13}N_4Cl$, or with picric acid having a formula of $C_6H_3N_3O_7$, or any other appropriate substances which will be affected by or dissolved in gasoline. Of course, the indicator could also be made of material which, when wetted with gasoline or the like, will show easily recognizable changes. In this manner the introduction of spurious or bootleg gasoline into the filling pipe may be easily detected.

For the purpose of giving those skilled in the art a better understanding of my invention, a description of preferred embodiments will be given in conjunction with Figs. 1-6 of the accompanying drawing. A device embodying my invention is placed on a filling pipe S leading to a tank. In the device a registering device N is incorporated. Rod 1 protrudes from a housing 2 which completely seals the whole mechanism. A spring 3 exerts an upward pressure against rod 1 and cap C. When the cap is removed, rod 1 moves up and when pressed down again pawl 1' engages ratchet 4 and turns it about a central shaft 5 which causes the registering of each movement with a higher number. On numbering device N is a protecting angle 6 which is mounted as close as possible to rod 1, so that no accidental interference is possible. A pocket 7 formed by a thin ridge 8, sidewalls 9 and 10 and ceiling 11 has to be far below the upper edge of pipe S so that a coupling, for instance, of a filling hose will not touch rod 1 and actuate it.

The preferred construction of such a cap is a bayonet lock formed by slots 13 and pins 14. The rim 15 of cup 16 acts like a spring washer exerting a constant pressure upwards and thereby forces pins 14 into indentation 13' and holds cap C securely in place. Slots 15' make rim 15 more flexible. The cup 16 is best made from resilient tempered metal. As the rim 15 is larger than opening of the innermost diameter of the pipe S, it will prevent accidental dropping of cup into tank below. The ledge 17 of the cap 55

holds cup 16 by extensions 18 which are slightly smaller than slots 19 through which, by a turn of 45 degrees in this case, cup 16 can be taken out of the cap for inspection. A funnel shaped cover 20 prevents drippings from gage 22 from dropping on an indicator strip 21 which is hung up on pins 23 fastened to channel 24. A slot 25 incorporated in cap C for gage 22 has a protecting lid 26 with an extension 26' which is set at such an angle that lid 26 can only open less than 90 degrees and will close by its own weight. A leaf spring 27 closes opening 25 and functions as an additional vapor seal.

A modified embodiment of the present invention is illustrated in Fig. 5 where cap C is screwed to pipe S. Counting device N operates at the same time as roll 30. In other words, the pawl and ratchet actuate the counting device and roll simultaneously. With each movement a numbered and perforated strip 30' advances with a number corresponding with that of counting device. It is preferred that strip 30' should be torn off and pasted on the record sheet of the delivering company to show that the cap was officially opened and that gasoline or the like was officially introduced in pipe S. Lever 31 turning on hinges 32 is held down by lock 33 passing through extension 34 and passing over or through the other end of the lever whereby it is held fast

to the extension 34. The lock prevents unofficial opening of cap C and the introduction of spurious or bootleg gasoline or the like into pipe S. The extension piece 31' integral with lever 31 will strike rib 35 mounted on casing 36 which supports a cover for the filling pipe and cap, and prevent turning of cap C. When the lock 33 is removed, lever 31 may be raised above casing 36 and the cap unscrewed.

Fig. 6 shows section of measuring stick 10 corrugated so that it can be made not only very rigid but also very light in weight at the same time. Opening 25 can be made correspondingly narrow. The reflecting angle varies in a gage so formed and makes the observation of the 15 dividing line of the wet and dry part of the stick easy observable.

I claim:—

In a registering device capable of being attached to the outside of a filling pipe having a 20 removable cap, the combination comprising a registering device mounted on said filling pipe, a 25 housing for said registering device, an upwardly projecting rod adapted to co-operate with the lower edge of said cap and to actuate said registering device when said cap is removed, and a protecting angle for said rod mounted on said housing to prevent accidental actuation of said registering device.

MORITZ GAERTNER. 30
